UNITED STATES PATENT OFFICE.

MATTHEW H. JOHNSON, OF CONCORD, NEW HAMPSHIRE, ASSIGNOR TO
ALPHEUS M. JOHNSON AND HENRY H. JOHNSON, OF SAME PLACE.

ROAD BREAKING AND GOUGING MACHINE.

SPECIFICATION forming part of Letters Patent No. 655,404, dated August 7, 1900.

Application filed February 28, 1900. Serial No. 6,803. (No model.)

To all whom it may concern:

Be it known that I, MATTHEW H. JOHNSON, a citizen of the United States, residing at Concord, in the county of Merrimac and State of New Hampshire, have invented certain new and useful Improvements in Road Breaking and Gouging Machines; and I do hereby declare the following to be a full, clear, and exact description of the invention, such as will enable others skilled in the art to which it appertains to make and use the same.

This invention relates to road-breaking machines more especially adapted for winter use, the object being to facilitate the breaking of streets and highways in rural districts and to gouge out gutters or ditches and level off pitch-holes. In towns and cities the invention will also be found serviceable.

The invention consists of certain adjustable wings of novel form and construction, together with their operating mechanism and means for attaching the wings to an ordinary sled, as fully set forth in the following specification and claims and clearly illustrated in the drawings forming a part of the same, of which—

Figure 1 is an elevation showing a portion of the side of a sled to which my improvements are attached, Fig. 2 being a sectional elevation showing a detail of my invention on an enlarged scale. Fig. 3 is a broken cross-sectional view showing a portion of the body of a sled and my improved wings with their connections, Fig. 4 being a broken plan view showing a portion of the body of a sled with my improved wings and their adjusting mechanism. Fig. 5 represents in perspective the machine complete.

Similar reference-letters designate corresponding parts in all the views.

A convenient and important feature of my improvements is the novel means for performing the adjustment of the wings or scrapers separately or independently one of the other, thereby making it possible to adjust said wings in practical alinement at a right angle or otherwise with the sled and to use them separately or together without interfering one with the other. The adjustable wings may be readily secured at any angle or elevation which occasion or circumstances may re-

quire, and the machine will work equally as well in light, damp, or compact snow, is most simple in construction and easily manipulated, yet strong, durable, and serviceable. 55

Referring to the accompanying drawings, A is the runner of a sled, and B indicates the floor-boards, which run crosswise of and are secured to the longitudinal rails C, forming the body-frame of a sled. Instead of connecting the wings or scraper directly to the sled-body I consider it preferable to provide a stout plank D and attach the same transversely to the under side of the rails C by means of bolts or rivets d, as seen in Fig. 4, said plank 65 D being permitted to project at each side of the sled-body for the convenient adjustment of the wings at the desired angle. The ends of the plank D are curved, as seen in Fig. 4, and provided upon opposite sides with curved 70 metal plates E, which are secured thereon by rivets e, and with a metal yoke F, secured by bolts G to opposite edges of said plank, the transverse or end portion f of said yoke being curved to correspond with the curved 75 plates E and separated from the latter the proper distance to form an opening for the reception and adjustment of one of the wing hangers or supports H, the hangers or supports H', carrying the inner or adjacent ends 80 of the wings, being secured to the plank at fixed points, as shown, and forming the radius of the curved ends of the plank, as well as the plates E and end portion f of the yoke F. Each pair of hangers H H' is provided 85 with one or more perforations h for the reception of a bolt I, and the studs h' of the hangers H pass upward, one through each of the curved passages S, in which they may be secured at the desired point by a threaded 90 nut h², while the studs h³ of the hangers H' pass upward through a perforation in the plank D and are secured therein by a threaded nut h⁴.

J indicates my improved adjustable wings 95 or scrapers, which are loosely connected at their top to the rods or bolts I by suitable strap-irons K, firmly riveted to said wings. The inner or adjacent ends of the wings J are separated but a couple of inches, more or less, 100 and their under portions are cut away, as at j in Fig. 3, thus forming an arched passage

for the surplus scrapings of snow or ice which shall have been drawn to the center of the road by the wings. The under portion of the outer end of each wing J is also cut away, as 5 in Fig. 3, and the principal working edges of the wings are provided with an iron or steel face-plate L, as shown in Figs. 1 and 3.

M indicates extension-arms which are useful in leveling off the the ridges of snow which 10 tend to form beyond the outer ends of the wings when the snow is crowded from the center of the road outward and which would drift back into the road when high winds prevail. These arms M are pivotally attached, as at 15 m, to the wings J and rest when in use upon the iron N, secured by bolts or rivets n to either wing J, and are held in place by a swiv- 20 eled button O, as seen in Figs. 3 and 4, and when not required for use said arms may be 25 elevated after first turning the button O to the position shown by dotted lines in Fig. 3.

As a means of adjusting the wings to the required vertical angle a chain or cable P may connect the forward side of each wing J 25 with a suitable taking-up or winding device attached to the sled-body at a point forward of said wings. To this end I show an eyebolt p, secured to a wing J and provided with a link p', to which one end of the cable P is 30 attached, the other end of said cable being secured to a drum or sleeve Q, said sleeve having at one end a ratchet-wheel q and at its opposite end a perforated wheel q', one of said sleeves being mounted upon a journal 35 r, formed at each end of a square bar R, secured by suitable loops T to the floor of a sled, as seen in Fig. 4.

A nut r' may be threaded to each journal r of the bar R for holding the sleeves Q there- 40 on, and a suitable bar may be inserted in either socket or perforation q' of the wheel q' for winding the cable P upon the sleeve Q, or vice versa, said sleeve being held station- 45 ary by means of a pawl U, pivotally attached, as at V, to either side of the sled-body, one end of said pawl being adapted to engage the teeth of the ratchet-wheel q, while its oppo- 50 site end may be pressed downward for disengaging the pawl from the ratchet and per- mitting the rotation of said sleeve for vary- 55 ing the vertical angle of the wing J.

By the peculiar form and adjustment of my improved scrapers or wings this machine not only plows the snow from the sled-tracks, 55 but also presses it down, leaving a smooth compact road-bed which will wear well, the sun not exerting so deteriorating an effect upon a hard compact surface of snow as it will upon a more porous surface, such as fol- 60 lows the common practice of road-breaking, a fact which is readily appreciated by the public who use the highways and streets.

For gouging off the shoulders and filling pitch-holes this machine can be so gaged as 65 to gradually remove the snow or ice and pack it firmly into the depressions resulting from heavy teaming, or in cases where snow alone

causes the unevenness the wings J can be so set as to accomplish the desired object at one operation. In breaking roads with my im- 70 proved machine when the snow is light the wings may be set at rightangles with the sled, as seen in Figs. 3 and 4; but when encountering heavier snow or drifts they are ad- justed so that their outer ends incline rear- 75 ward, and for filling pitch-holes, &c., the wings are inclined forward, so as to draw the scrapings into the center of the road, the sur- plus passing under the arched or cut-away portions of the adjacent ends of the wings, 80 the foregoing adjustments being readily ac- complished by the movement of the hangers H within the curved passage S at each end of the plank D, and by the use of this plank for supporting the wings it is obvious that a 85 machine adapted for breaking roads and em- bodying the foregoing improvements may be readily contrived where an ordinary four-run- 90 nered sled is obtainable.

Having described my improvements, what 90 I claim is—

1. In a road-breaking machine, a pair of wings or scrapers located normally in trans- 95 verse alinement and pivotally connected to the machine at or near their adjacent ends, means for adjusting said wings at an angle forward or backward, and means for elevat- 100 ing the lower edge of said wings comprising rotary drums, ratchets and pawls for controlling the same, and a chain or cable connect- 105 ing said wings and drums.

2. In a road-breaking machine, a pair of wings or scrapers having the lower corners of their adjacent ends cut away and located normally in transverse alinement and pivot- 110 ally connected to the machine at or near their adjacent ends, means for adjusting said wings at an angle forward or backward comprising movable hangers, and means for elevat- 115 ing the lower edge of said wings comprising rotary drums, ratchets and pawls for controlling the same, and a chain or cable connect- 120 ing said wings and drums.

3. In a road-breaking machine, a pair of wings or scrapers disposed transversely and 115 in normal alinement, said wings being piv- 120 tally attached to the machine near their ad- jacent ends and having their lower adjacent corners cut away and the outer portions of their lower edge formed upon a higher plane 125 than are the central working portions, means for adjusting said wings at an angle forward or backward said means comprising mov- 130 able hangers, means for elevating the lower edge of said wings comprising rotary drums, ratchets and pawls for controlling the same and a chain or cable connecting said wings and drums, and extension-arms pivotally at- 135 tached to said wings, substantially for the purpose set forth.

4. In road - breaking machines, a trans- versely-disposed plank bolted to the under side of the body portion and projecting be- 140 yond the sides of said machine, a pair of

- transverse wings or scrapers having their adjacent ends pivoted at a fixed point to said plank, suitable hangers pivotally attached to said wings and adapted for adjustment near 5 either end of said plank and for securing said wings in alinement or at an angle therewith, and means substantially as shown for drawing the lower edge of said wings forward, substantially for the purpose set forth.
- 10 5. In a road-breaking machine, a pair of wings or scrapers pivotally connected near their adjacent ends to said machine and disposed transversely in normal alinement, the under corners of said adjacent ends being cut 15 away and said wings being adapted for vertical and horizontal adjustment whereby the snow may be closely packed at most desirable points in the road.
- 15 6. In a road-breaking machine, a pair of wings or scrapers pivotally connected near 20 their adjacent ends to said machine and disposed transversely in normal alinement, the lower edge of that portion of the wings which extends beyond the machine being formed on a higher plane than that of the remainder of 25 the working edge of said wings, extension-arms pivotally attached to the outer ends of said wings, and means for adjusting said wings vertically and horizontally whereby the ridges of snow which usually form at 30 either side of the sleigh-tracks may be leveled.
- In testimony whereof I affix my signature in presence of two witnesses.
